United States Patent Office.

HEZEKIAH DODGE, OF ALBANY, NEW YORK.

Letters Patent No. 101,716, dated April 12, 1870; antedated April 4, 1870.

IMPROVED MOP-HEAD.

The Schedule referred to in these Letters Patent and making part of the same.

To all whom it may concern:

Be it known that I, HEZEKIAH DODGE, of Albany city and county, and State of New York, have invented a new and improved Mop-Head, or simple device for holding mop-cloths and wringing the same; and I do hereby declare that the following is a full, clear, and exact description thereof, which will enable others skilled in the art, whom I may authorize, to make and use my invention, reference being had to the accompanying drawings forming part of this specification.

This invention relates to a new and improved mop-head, whereby the mop cloth is with unusual ease inserted or removed.

In the accompanying sheet of drawings—

Figure 1 is the butt of the mop-handle of a peculiar shape.

Figure 2 is a perspective view of the interior of the cleft mop-head hinged together.

Figure 3, a sectional view, or the interior of one of the cleft halves of the mop-head.

Figure 4, a perspective view of the improvement as in actual use.

Similar letters of reference indicate corresponding parts.

A is the mop-handle.

B, the cleft mop-head hinged together.

C is the cleft-tube of the mop-head. This tube receives the mop-handle A.

D is the bag-like mop-cloth with the butt of the mop-handle pushed down and twisted round in it, so as to wring out the water.

E is a catch to keep the mop-handle up when scrubbing, and when it is not used for wringing the mop-cloth.

f and f' are simple hinges of leather or other material that hinge the cleft mop-head together.

I construct the mop-head B B, fig. 2, of two pieces of wood, or of any other suitable material, and hinge them together, and slide it down upon and clasp it on the mop-handle A, much as shown in drawings.

In operating, to attach a mop cloth, I open the cleft mop-head as at B B, fig. 2, insert the ends of the cloth and closing the mop-head, clasp it tight, holding it fast. By pushing the mop-handle down into the bag of the cloth and twisting it, the cloth may be wrung as at D, fig. 4.

The invention combines simplicity and cheapness; a mop cloth can be attached or removed in a minute.

What I claim, as my improvement in mop-heads, is—

The construction of the head B, in combination with the handle A, as shown and described.

HEZEKIAH DODGE.
